MAGNETIC DELAYED ARMING DEVICE FOR
FUSES AND BOOSTERSSidney Sobelman, Morris Plains, N. J., assignor to the
United States of America as represented by the Secretary of the Army

Application October 21, 1952, Serial No. 316,110

8 Claims. (Cl. 102—79)

(Granted under Title 35, U. S. Code (1952), sec. 266)

The invention described herein may be manufactured and used by or for the Government for governmental purposes without the payment to me of any royalty thereon.

The present invention relates to a delay arming device for spin-stabilized projectiles.

The use of delay arming devices in fuses and boosters to maintain the explosive train in a projectile in unarmed condition until the projectile is free of the weapon and has traversed to a safe distance, is well known in the art. Such devices may involve mechanism which is armed by means responsive to rotation of a projectile, as for example arming blocks movable into position by centrifugally responsive gear trains, or ball rotors responsive to centrifugal force of a spinning projectile to precess or rotate into armed position.

In projectiles employing a point detonating fuse, an explosive train is provided which usually comprises a detonator of an extremely sensitive substance adapted to function instantaneously when struck by a firing pin upon impact or when flash initiated, and an explosive charge of an insensitive nature which is set off by the detonator. If the fuse contains a booster, the detonator first sets off the booster charge which again is insensitive, and the booster in turn detonates the explosive projectile charge.

In any case the sensitive detonator must be protected against premature detonation in the event an obstruction is encountered either in the bore of the weapon, or in flight in the vicinity of friendly personnel immediately after the projectile emerges from the weapon. If premature detonation of the sensitive substance does occur in the bore of the weapon or before the projectile is clear of friendly personnel, a delay in movement of the detonator to completely armed position is desirable since it will confine the explosion to the detonator alone and will prevent the flash from being communicated to the explosive charge.

It is accordingly an object of this invention to provide a delay arming device for a fuse or booster which is both bore safe and detonator safe.

It is also an object of this invention to provide a delay arming device for a fuse or booster constructed and arranged to maintain a break in the continuity of the explosive train until the projectile has traveled to a safe location.

It is also a further object of this invention to provide a delay arming device for a rotating projectile fuse or booster including an arming ball rotor movable from safe to armed position in response to centrifugal force of the rotating projectile.

Still another object of this invention is to provide a delay arming device for a spin-stabilized projectile including an arming ball rotor which is held in safe position by the force of attraction between magnets located in the body of the fuse and in the rotor, until cessation of set back, whereupon the rotor is precessed to armed position by the centrifugal force of the rotating projectile.

With these and other objects in view which will become apparent as the following specification develops,

2

reference is made to the accompanying drawing forming a part of the specification wherein like numerals are used to designate corresponding or similar parts in the several views and wherein:

5 Figure 1 is a transverse sectional view of the magnetically restrained rotor of my invention as applied to a booster.

Figure 2 is a section taken on line 2—2 of Figure 1.

10 Figure 3 is an isometric view of the body magnets, rotor magnet and keeper.

Figures 4 and 5 represent a modification of the arrangement in Figure 1 with the rotor magnet eliminated and with a section of the rotor magnetized instead.

Figures 6, 7 and 8 illustrate another modification using 15 a cylinder magnet as a liner for the detonator.

Referring to Figures 1, 2 and 3 wherein the same numerals are used to designate the same parts in the several views reference character 1 designates a booster assembly for a projectile fuse comprising a main cylindrical body portion 2 externally threaded at 3 to screw

20 threadedly receive the correspondingly threaded portion of a fuse (not shown). The upper portion of body 2 is provided with a cylindrical bore 4 of substantial diameter having a depth about one third the depth of the body, leading into a counterbore 5 of reduced diameter and of approximately the same depth as bore 4. Counterbore 25 5 is internally threaded at 6 to screw threadedly receive a cylindrical insert 7 having a lesser depth than counterbore 5 and so disposed within the counterbore to provide

30 a narrow cylindrical space 8 between the lower end of insert 7 and the bottom of counterbore 5. Insert 7 is provided centrally with a downwardly opening spheroidal cavity which allochirally mates with a shallower upwardly opening axial cavity in the lower third of body portion 2, to form a spherical cavity 9 for receiving an arming ball rotor 10 of a diamagnetic substance such as brass or any of the well-known plastics. The ball rotor is provided with a diametral bore 11 terminating in a reduced axial bore 12 which forms an annular shoulder

35 40 13 to support the lower end of a detonator capsule 14, tightly received in bore 11.

The magnetic system for restraining rotation of the arming ball rotor comprises a bar rotor magnet 15 snugly fitted into an off-center bore 16 formed transversely in 45 the ball rotor just below the lower side wall of detonator capsule 14 when restrained in safe position as seen in Figure 1. The rotor magnet is provided with a keying slot or cavity 17 midway between the ends thereof, and in its top surface, to receive the rounded surface of the

50 55 detonator capsule wall to thereby retain the magnet in place within the rotor (see Fig. 3). The opposed ends of the rotor magnet are curved as at 18 and 18a to conform with the contour of the ball rotor. The body 3 of the booster assembly is provided with horizontal recesses 19, 19a directly below the bottom wall of counterbore 5 and extending transversely on opposed sides of rotor magnet 15, to receive bar magnets 20, 20a, with inner ends 21, 21a curved to conform with the curved ends of the

60 65 The magnets may be made of a composition consisting of aluminum, nickel and cobalt, commonly known as "Alnico," or a similar substance having paramagnetic properties. To complete the magnetic circuit, a toroidal keeper 22 of soft iron, or the like is received in space 8 to encompass ball rotor 10 and with its bottom wall abutting the top surface of magnets 20, 20a. Keeper 22 acts to preserve the intensity of magnetization in the well-known manner.

A cup shaped member 23 is screwed to the lower half 70 of threads 3 on body 2 with its bottom axially spaced from the lower end of body 2 to provide a chamber 24 in which is received an explosive booster charge 25.

An axial passage 26 is formed in body 2 to extend between the spherical cavity 9 and chamber 24 such that when the ball rotor is moved in clockwise direction to armed position, passage 26 and bores 11 and 12 are in axial alignment to provide a continuous flash passage between the detonator and booster. Alternatively a lead-in explosive capsule 27 of less sensitivity than the booster charge may be interposed in passage 26 if desired. Also, insert 7 is provided with an axial flash passage 28 to permit passage therethrough either of a firing pin or flash in the well-known manner.

The operation of the device is obvious from the above description. As can readily be seen, the north and south poles of the magnets are relatively disposed so as to achieve maximum magnetic attraction when the ball rotor is in unarmed or "safe" position. This attraction restrains the rotor magnet and the rotor from movement especially in view of the off-center location of the rotor magnet in the rotor assembly. Although normal handling in shipment and in the field, or in the event the fuse or projectile is dropped, may cause the rotor to move with respect to the fuse body, the force of the magnetic field will immediately swing the rotor assembly back to safe position. Additionally if the extremely sensitive detonator is inadvertently set off, the break in continuity of the flash passage resulting from the force of attraction of the magnets will preclude detonation of the lead-in and booster charges.

When a projectile containing the fuse of my invention is fired from a weapon, set back forces will increase frictional resistance between the ball rotor and the abutting surfaces of the spherical cavity, and these forces together with the magnetic force of attraction are sufficient to override the effects of centrifugal force to prevent precession of the ball rotor until the projectile is free of the weapon. Upon cessation of set back, when the projectile is free of the weapon, centrifugal force will now be sufficient to overcome the effects of the magnetic attraction to cause the ball rotor to precess to armed position. Obviously the parts may be designed for sufficient time to elapse before the fuse is fully armed, to enable the projectile to traverse to a safe distance so that if obstruction is encountered to detonate the fuse, friendly personnel will not be endangered by premature explosion.

It is to be understood that proper adjustment must be made due to the shift in center of gravity of the ball rotor caused by the differences in specific gravity between the brass rotor and the "Alnico" rotor magnet. Additionally, notwithstanding the decrease in effectiveness of the magnetic field, as the rotor magnet moves farther away from the body magnets, a certain amount of magnetic attraction will remain which may prevent the ball rotor from moving to fully armed position. To obviate this tendency a compensating hole 29 may be drilled in the ball rotor. The location of this hole must be such as to angularly shift the axis of the maximum moment of inertia in a counterclockwise direction, as the parts are viewed in Figure 1. As this axis tends to align with the axis of spin of the projectile, the rotor, when rotating at average speed will tend to over shoot the fully armed position. By making the hole of proper size, depth and location, the magnetic couple tending to hold the rotor from the fully armed position is overcome or nullified.

Referring to the modification in Figures 4 and 5 the booster assembly is designated as reference character 1', and is provided with cylindrical body portion 2' externally threaded at 3' and having upper cylindrical bore 4', and counterbore 5'. Counterbore 5' is provided with threads 6' for receiving insert 7'. Arming ball rotor 10' which in this modification is of magnetizable metal, is received in spherical cavity 9' formed partly in insert 7' and partly in body 2', and the rotor 10' is provided with diametral bore 11'. Detonator capsule 14' is snugly received in bore 11'. However in place of a rotor magnet 15 an off-center transverse section of the ball rotor

15' directly below the side wall of capsule 14' is magnetized. Similarly as in the species of Figure 1 recesses 19' and 19a' are provided in body 2' to receive magnets 20' and 20a' curved as at 21' and 21a' to conform with the ball rotor 10'. A keeper 22' is received in a space 8' formed between insert 7' and the bottom of counterbore 5', and in like manner a booster cup 23' is screwed onto body 2', to form chamber 24' for receiving a booster charge 25'. An axial passage 26' to receive a lead-in 27' is formed in body 2' between chamber 24' and spherical cavity 9', and insert 7' is also provided with an axial passage 28' to permit initiation of the detonator. If need be a compensating hole (not shown) may also be drilled in rotor 10' to compensate for the tendency of the remaining magnetic attraction between the magnetized rotor and magnets 20', 20a', which would otherwise prevent full arming of the ball rotor. The operation of this system is exactly the same as the species illustrated by Figures 1 and 2, hence it will not be described.

Figures 6, 7 and 8 delineate yet another modification wherein a cylinder magnet forming a part of the magnetic restraint system, is also used as a liner for the detonator capsule.

Referring to the drawing 101 designates a booster assembly provided with a main cylindrical body portion 102 externally threaded at 103. The upper third of body portion 102 is provided with a cylindrical bore 104 of substantial diameter leading into a counterbore 105 of slightly reduced diameter but having a depth substantially equal to the depth of bore 104. The side wall of counterbore 105 is screw-threaded at 106 to receive an externally threaded plug or insert 107 approximately one half the depth of counterbore 105, and so disposed in the counterbore to form a cylindrical space 108 between the lower surface of plug 107 and the bottom of counterbore 105. Plug 107, and the section of body portion 102 beneath the lower extremity of counterbore 105 are provided respectively with axially opposed, allochirally mated spherical cavities 109 and 110 adapted to receive between them for rotation only an arming ball rotor 111 which may be made of brass or some other diamagnetic substance such as any of the well known plastics.

Rotor 111 is provided with a diametral bore 112 of substantial diameter lined with a cylindrical magnetic sleeve or insert 113 of "Alnico," or the like crimped into place in the rotor as at 114, 115. Within the bore of sleeve 113 there is received a detonator capsule 116 having one side abutting a shoulder 117 formed in the sleeve, and the opposed side engaged by a split-ring detonator retainer 118 adapted to hold the capsule in place within the liner. A toroidal keeper 119 concentric about rotor 111 and with its axial bore 119' of greater diameter than ball rotor 111 is tightly received in space 108, and in the lower half of its wall on one side, the keeper is provided with a recess 120 in longitudinal alignment with a mating recess 121 in body 102 for receiving a bar magnet 122, extending into bore 119' and curved as at 123 to conform to the contour of ball rotor 111. On the side opposed to recess 120, the wall of keeper 119 is slotted as at 124 to receive a magnet 124a which engages the side wall of counterbore 105 at its outer extremity, the inner end extending into bore 119' and curved as at 125 to conform with the contour of arming ball rotor 111.

The rest of the booster assembly 101 is similar in design to the species illustrated in Figures 1 and 2 and in like manner comprises booster cup 126, booster chamber 127, booster charge 128, axial flash passage 129 to receive a lead-in 130 and compensating hole 131. Insert 107 is also provided with a frusto-conical axial passage 132 which will communicate with the axial bore in the ball rotor when the rotor is in fully armed position. As the magnets are not duplicates, no error can arise in assembly. The magnetic field of flux is axially past

the detonator and circumferentially through the keeper. Obviously the description of operation for this modification is similar to the operation for the first species and need not be described.

While my invention has been illustrated as being applicable to a booster assembly for the type of fuse commonly associated with a spin-stabilized projectile, it is to be understood that other adaptations within the purview and scope of this specification are also possible. For example the magnetic restraining system may also be utilized in aerial drop bombs having fins to cause the bomb to spin in descent. Numerous other modifications and alterations of the structures disclosed and illustrated will be apparent to one skilled in the art, and it is obvious that such modifications may be made without departing from the spirit of the invention as defined in the following claims.

What I claim is:

1. In a point detonating fuse for a rotating projectile, a main body portion having a spherical cavity and an axial flash passageway forwardly of said cavity, a spheroidal rotor in said cavity having a diametral bore with its axis lying crosswise of the axis of said flash passage when said fuse is unarmed, a detonator in said diametral bore, first magnetic means in said rotor, and second magnetic means in said body interacting with said first magnetic means to normally urge said rotor into unarmed position; upon firing said projectile to precess said rotor to armed position, said magnets retarding precession of said rotor to delay arming of said fuse.

2. In a point detonating centrifugally armed fuse, a body having an axial flash passage therein, a ball rotor mounted for universal rotation in said body rearwardly of said flash passage, said rotor having a diametral bore lying crosswise of the axis of said flash passage when said fuse is unarmed and determining an axis of maximum moment of inertia, and magnetic means in said body interacting with magnetic means in said rotor to hold said rotor in unarmed position; upon firing the projectile supporting said fuse said magnetic means continuing to interact to retard precession of said rotor to armed position.

3. In a point detonating centrifugally armed fuse for a spin-stabilized projectile having a longitudinal axis, a booster assembly comprising a body received in said fuse, said body having a spherical cavity formed therein, a centrifugal ball rotor rotatable in said cavity from first safe position to second armed position, said ball rotor having a diametral bore lying crosswise of said longitudinal axis when said rotor is in safe position, said body having an axial passage forwardly of said ball rotor in axial alignment with said diametral bore when said rotor is in armed position, a detonator in said diametral bore, and interacting magnetic means on said body and said rotor urging said rotor into said crosswise position, said ball rotor is made of a diamagnetic substance, and said magnetic means comprises a rotor magnet received in a hole formed transversely in said rotor subjacent said detonator, interacting with a pair of magnets each lying in recesses formed in said body on opposed sides of said rotor magnet in horizontal alignment therewith.

4. In a point detonating centrifugally armed fuse for a spin-stabilized projectile having a longitudinal axis, a booster assembly comprising a body adapted to be received in said fuse, said body having a spherical cavity formed centrally therein, a centrifugal diamagnetic ball rotor rotatable in said cavity from first safe position to second armed position, said ball rotor having a diametral bore lying crosswise of said longitudinal axis when said rotor is in safe position, said body having an axial passageway forwardly of said ball rotor in axial alignment with said diametral bore when said rotor is in

armed position, a paramagnetic sleeve liner snugly fitting said diametral bore, a detonator in the bore of said sleeve liner, and a pair of magnets in said body in recesses on opposed sides of said rotor interacting with said sleeve magnet to urge said rotor into cross-wise position.

5. A fuse for a spin stabilized projectile comprising a fuse body, a centrifugally responsive arming rotor within said fuse body adapted to precess from safe to armed position upon firing of said projectile, a rotor magnet, a pair of body magnets normally axially aligned with each pole of said rotor magnet and spaced therefrom, said magnets normally holding said rotor in safe position; upon firing said projectile to precess said rotor to armed position, said magnets retarding precession of said rotor to delay arming of said fuse.

6. A point detonating centrifugally armed fuse for a spin stabilized projectile having a longitudinal axis comprising a body in said fuse having an axial passageway, a ball rotor mounted for universal rotation in said body rearwardly of said passageway, said rotor having a diametral bore lying crosswise of said longitudinal axis when said fuse is unarmed and determining an axis of maximum moment of inertia, magnetic means in said body interacting with magnetic means in said rotor to prevent coincidence of said diametral bore with said longitudinal axis during handling and retard precession of said rotor to armed position in response to centrifugal force of a spin stabilized projectile, said ball rotor is made of a diamagnetic substance, and said magnetic means comprises a rotor magnet received in a hole formed transversely in said rotor subjacent said detonator, interacting with a pair of magnets each lying in recesses formed in said body on opposed sides of said rotor magnet in horizontal alignment therewith.

35 7. A delay arming, point detonating fuse for a spin stabilized projectile comprising, a main body portion having a spherical cavity therein, an arming ball rotor mounted for universal rotation within said cavity, a first bore through said rotor, a detonator in said first bore, a second bore through said rotor, a rotor magnet within said second bore, a pair of body magnets on each side of said rotor in spaced alignment with said rotor magnet, means to preserve the intensity of said body magnets, said body magnets interacting with said rotor magnet to normally hold said rotor in unarmed position; upon firing said projectile, said rotor precessing to armed position against the retarding action of said magnets.

8. A delay arming, point detonating fuse for a spin stabilized projectile comprising, a main body portion having a spherical cavity therein, an arming ball rotor mounted only for universal rotational movement within said cavity, a detonator within said rotor, a rotor magnet within said rotor, a pair of body magnets on each side of said rotor in spaced alignment with said rotor magnet, means to preserve the intensity of said body magnets, the intensity of magnetization of said magnets and the spacing therebetween being sufficient to overcome rotation of said rotor during normal handling of said fuse and projectile; upon firing said projectile, said rotor precessing to armed position against the retarding force of said magnets whereby the arming time of said fuse is prolonged.
